UNITED STATES PATENT OFFICE

JOHN SHELLENBERGER, OF ROME, GEORGIA.

PACKING OR SHIPPING RECEPTACLE.

No. 923,588.

Specification of Letters Patent.

Patented June 1, 1909.

Application filed November 18, 1907. Serial No. 402,660.

To all whom it may concern:

Be it known that I, JOHN SHELLENBERGER, a citizen of the United States, residing at Rome, Floyd county, Georgia, have invented 5 certain new and useful Improvements in Packing or Shipping Receptacles; and I do hereby declare the following to be a full, clear, and exact description of the invention, such as will enable others skilled in the art 10 to which it appertains to make and use the same.

This invention relates to certain improvements in packing or shipping receptacles, and more particularly relates to wooden 15 packing or shipping cases, boxes, crates or the like; and the objects and nature of my invention will be readily understood by those skilled in the art in the light of the following explanation of the structure shown in the accompanying drawings of what I now consider 20 my preferred embodiment from among other formations and arrangements within the spirit and scope of my invention.

The invention consists in certain novel 25 features in construction, or in combinations or arrangements of parts or details as more fully and particularly set forth hereinafter.

Referring to the accompanying drawings:—Figure 1, is a perspective view of a 30 closed case or box constructed in accordance with my invention. Fig. 2, is a sectional perspective on the line 2—2, Fig. 1, the cover sections being shown extending upwardly in continuation of the sides. Fig. 3, 35 is a sectional view taken in the plane of the line 3—3, Fig. 1. Fig. 4, is a perspective view of the sheet like blank from which the bottom, sides and top of the box of Fig. 1, are formed, dotted lines indicating the ends 40 or heads. Fig. 5, is a detail elevation, on an enlarged scale, of a corner of one end of the box of Fig. 1.

It is an object of this invention to provide 45 certain improvements in wire bound packing or shipping receptacles with the end in view of decreasing the cost of manufacture and setting up or assembling and increasing the durability and advantages of receptacles of this general type.

50 A further object of the invention is to provide a wire bound packing or shipping receptacle with a sectional or two part top or cover and wherein the bottom, sides and cover of the receptacle are bent or formed 55 from a flat or sheet like blank, the opposite end portions of which form or constitute the

two cover sections or parts, and wherein such blank comprises several overlying or superimposed sheets, pieces or sections of veneer or the like, certain of which are formed with 60 cuts to form bending lines, and wires running longitudinally of the blank and secured thereto to cross or extend transversely of the bottom, sides and cover sections of the completed box or receptacle. 65

A further object of the invention is to provide certain improvements in packing or shipping receptacles wherein the bottom and sides are secured to the edges of previously 70 formed end heads, said bottom and sides being composed of a blank bent around said end heads and comprising superimposed sheets, certain of which are cut, longitudinally of the box to form bending lines, wires being arranged longitudinally of the exterior 75 of said blank, and transversely of the bottom, and sides, and staples passed through said superimposed sheets and clenched and securing the same together and the wires thereto. 80

A further object of the invention is to provide a wire bound packing or shipping receptacle wherein the opposite ends of the blank forming the bottom and sides of the receptacle are utilized to form a two part or sectional cover. 85

A further object of the invention is to provide an improved flat or sheet-like blank adapted to be bent around the edges of end heads to form the bottom, sides and cover of 90 a shipping or packing receptacle.

A further object of the invention is to provide certain improvements in details of construction and arrangements of parts, whereby a highly efficient and improved shipping 95 or packing receptacle will be produced.

In the specific example shown in the accompanying drawings for the purposes of explanation to make clear to those skilled in the art the various features involved in my 100 invention; 1, are the ends or end heads of the receptacle. These heads can be of any suitable or desirable construction although in the drawings I show them of the solid rectangular form, but I do not wish to so limit my invention. The bottom, 2; sides 105 3, and cover sections 4, overlap the edges of these previously completely formed end heads 1, and are secured thereto by any suitable means, such for instance, as by nails 5. 110

In the form illustrated, I show a closed or tight receptacle wherein the bottom and

sides are solid or each comprising a single sheet of veneer or the like, and wherein each cover section comprises a single sheet of veneer or the like, the several bottom, side and cover sheets overlapping at their edges to form approximately closed junctures, in the completed receptacle, although I do not wish to so limit all features of my invention, as a closed receptacle, might be otherwise 10 formed in accordance with certain features of my invention without forming the bottom, sides and cover of separate sheets, and according to other features of my invention, I do not wish to limit myself to the production of a closed receptacle.

In the specific example illustrated, the bottom of the receptacle is closed by a single board or sheet 2, such as a sheet of veneer, each side by a single board or sheet 3, as a 20 sheet of veneer, and the cover by two boards or sheets 4, as sheets of veneer. These various sheets are connected together by and are superimposed on several strips or sheet like pieces 6, arranged transversely of the under 25 (outer) faces of all of said sheets, and wires 7, are arranged longitudinally of and are secured on the outer faces of the sheets or strips 6. The sheets 2, 3, 4, and 6, are firmly fastened and secured together and the 30 wires 7, are tightly secured down on the sheets or strips 6, by inwardly driven staples 8. The staples straddle the wires and are driven inwardly through the superimposed sheets down tightly on the wires and the inner 35 ends of the staples are tightly clenched at the inner surfaces of the bottom, side and cover sheets so that the staples not only tightly and rigidly secure the wires but also tightly fasten the super-imposed sheets together. 40 These staples are usually closely arranged practically throughout the length of each wire 7, and sheet or strip 6, so that the members of each receptacle blank can be most securely and quickly fastened together by 45 stapling machinery.

In the specific example illustrated, I show the receptacle (excepting the end heads) formed from the flat blank of Fig. 4, comprising the bottom, side and cover sheets, 50 superimposed on three parallel sheets or strips 6, traversing the ends and central portion of said sheets, and these strips 6, can also be formed of veneer sheets, although for the sake of convenience they are generally 55 referred to as battens whether or not the receptacle bottom, sides and cover be bent up from one or more sheets of veneer superimposed on one or more battens. In forming the blank illustrated, the bottom, sides and 60 cover sections are spaced apart, with the battens bridging said spaces, and the portions of the battens bridging said spaces are cut or scored preferably to form notches 9, in the portions of the battens at said spaces, and 65 these notches form the bending lines in the

outer sheets (battens) on which the blank bends in passing from the bottom to the sides and from the sides to the cover sections, but I do not wish to limit myself to forming the bending line cuts in the inner faces of the 70 battens. I preferably arrange the notches at each space adjacent to one side or edge thereof, preferably not midway the width of the space, so that as the battens bend at the notches, the sheets 2 and 3, or 3 and 4, will 75 come tightly together with the inner face of one sheet resting on and extending across the edge of the other sheet, and with its outer edge closing against the uncut face of the batten, see Fig. 5. For instance, the notches 80 9, in the battens in the spaces at the opposite edges of the bottom sheet 2, can be arranged close to the adjacent edges of the sides 3, so as to leave the shoulders or uncut exposed inner faces 10, of the battens adjacent the 85 edges of sheet 2, and in width about equal to the thickness of each sheet 3. The notches 9, in the spaces between sheets 3 and 4, can be arranged close to the edges of sheets 4, leaving the batten shoulders or uncut faces 10, between said notches and the adjacent edges of sheets 3, and in width about equal to the thickness of sheets 4. By reason of this arrangement, when the blank is bent upwardly to the position shown in Fig. 2, the walls of 90 the notches 9, between sheets 2 and 3, will close together, and the lower edges of sheets 3, will drop down squarely onto the batten shoulders 10 with the sheets 3, extending across the side edges of sheet 2, and fitted 95 tightly against the same, thereby forming a very strong and yet tight joint between the sides and bottom. When the cover sections are bent down to the position shown by Figs. 1, 3 and 5, the walls of the notches 9, between 100 sheets 3 and 4, will close together, and the inner faces of sheets 4, will close down on and extend across the top edges of sheets 3, with their edges abutting against the vertical shoulders 10, above sheets 3.

The blank of Fig. 4, is formed of sufficient length to enable its opposite ends to bend or close down at the top of the receptacle with their longitudinal free edges meeting about the center of or midway the width of the receptacle top.

I usually so arrange the sheets 4, as to overlap at their free edges 11, as shown in Figs. 1 and 3, and the battens 6, preferably terminate short of said overlapping edge portions 11, to render said edges flexible, or to prevent portions of the cover bulging or projecting upwardly above the horizontal plane of the top faces of the portions of the battens on the cover. The cover sections can be secured at each end by one or more nails 5, passed down through the overlapping edges 11, into the end heads, and these two (or more) nails can be easily withdrawn when the cover sections are to be raised.

As these receptacles are usually stacked one on the other with the bottom portions of the battens of an upper receptacle resting on the cover portions of the battens of a lower 5 receptacle, it is desirable that the cover portions of the battens be flat or level, hence the edges 11, of the sheets 4, project beyond the ends of the battens, leaving the space between the batten ends in which the edges 11, 10 can overlap.

If desired, the wire ends 12, of the wire on the intermediate batten can be extended, to permit twisting of the same together as shown in Fig. 1, for the purpose of providing a 15 detachable fastening at the central portion of the cover between the sections thereof.

The battens 6 and the wires 7, form the hinge connections at the top edges of the sides, on which the cover sections 4, swing 20 vertically in opening and closing, and if the battens should break through at the V-cuts or notches 9, by reason of repeated swing of either cover section, the wires 7, would still form the proper connection with the side. 25 As each cover section is less in width than the height of the receptacle, said sections can be swung down to vertical positions at the outer surfaces of the sides, to completely open the box, and thus be out of the way, enabling a 30 number of opened receptacles to be arranged closely together.

Whether or not the free edges of the cover sections overlap, and whether or not either or both of said edges 11, project beyond the 35 ends of the battens, advantages are attained by the employment of the two part cover, as objectionable fastening devices at the top edges of the sides and at the top corners of the receptacle and the intermediate portions 40 of the sides are firmly secured and bound to the intermediate portions of the outer edges of the cover sections, thereby preventing outward bulging of the upper portions of the sides and avoiding the necessity of employing 45 the objectionable hooks, clips or large staples to join the central portions of the covers and sides. Furthermore, by the arrangement about as shown I produce a strong wire bound permanent joint or connection along 50 each upper longitudinal corner of the receptacle and between the cover and sides.

Where the blank or web comprises spaced or separate sheets or sections to make up the receptacle walls, I find the arrangement of 55 the notches 9, in the manner about as described, to be a valuable improvement and of material advantage, but I do not wish to limit other features of my invention to such arrangement of notches 9, as such other features are not limited to the formation of the inner walls of the crate from separate veneer sheets 2, 3, 4. Also I do not wish to limit all 60 features of my invention to overlapping the free edges of the cover sections. Also in 65 some instances, it may be desirable to secure

one cover section 4, to the end heads, and permit the other section to form the cover. Also I do not wish to limit all features of my invention to any particular number of veneer sheets to form the inner walls of the receptacle, nor to any particular number of superimposed wire bound outer sheets or battens 6, of any particular width. It is also evident that various changes and modifications might be resorted to in the forms, constructions and arrangements of the parts described, within the spirit and scope of the claims, without departing from my invention, and hence I do not wish to limit myself to the exact construction disclosed.

What I claim is:—

1. A packing or shipping crate comprising end heads, bottom and side walls secured to said heads, and a two-part vertically swingable cover, each section of which forms a 85 continuation of and is narrower than a side wall, said sections having projecting free edges adapted to overlap at the central portion of the receptacle top, and wire bound battens secured to and arranged transversely 90 of the bottom and side walls and continued onto and terminating short of said free edges, and secured to said cover sections.

2. A packing or shipping receptacle comprising end heads, and a blank or web 95 adapted to be bent around and secured to the end heads, to form the bottom, sides and a swingable vertically movable two - part cover, the free ends of the two parts of which close down and approximately meet at the 100 central portion of the receptacle top, said web being cut partially through to form bending lines at the top and bottom corners of the receptacle, and having end and intermediate longitudinal exterior binding wires 105 bridging said bending lines and extending from the sides onto said parts of the cover, said web comprising inner and outer superimposed thin sheets, the ends of the outer sheets terminating short of the projecting 110 free ends of the inner sheets, and staples straddling said wires and passed through the sheets and clenched to tightly secure the sheets together and the binding wires there-to, whereby the end edges of said sheets are 115 braced against splitting.

3. A packing box comprising end heads, and an elongated web blank adapted to be bent around and secured to said heads to form the bottom and sides of the box and 120 having extended ends to form a two-section cover for the box, each section of less width than the width of the sides, said sections adapted to close down and approximately meet at their free edges along the central 125 portion of the box top, said blank having transverse cuts to form the folding lines at the upper and lower corners of the box, and consisting of spaced sheets to form the bottom, sides and cover longitudinal walls, ex- 130

terior battens traversing the outer faces of said sheets at the ends and intermediate portions thereof and bridging the spaces between and connecting the sheets, exterior 5 binding wires laid longitudinally on and along the exterior surfaces of said battens, and rows of staples arranged along and straddling said wires and driven inwardly through the battens and sheets and clenched 10 and tightly binding the wires, battens and sheets together whereby the ends of the sheets are reinforced against splitting.

4. A packing or shipping receptacle comprising end heads, and a blank or web adapted to be bent around and nailed to said heads to form the receptacle, and having transverse cuts extending partially therethrough to form the bending lines, spaced wires arranged at the exterior of and extending 15 throughout the length and adjacent to the edges of said blank and bridging said bending lines, said blank composed of inner wall-forming and outer batten-forming superimposed sheets arranged transversely of each 20 other, the inner sheets being spaced apart and adapted to meet and overlap at their longitudinal edges when the blank is bent around the heads, and rows of clenched staples arranged along said wires and tightly securing 25 said inner and outer sheets together and the exterior wires down thereon, whereby the end edges of said inner wall-forming sheets are braced against splitting when nailed to said heads.

35 5. A packing box comprising end heads, and a web blank adapted to be bent around and secured to said heads to form the box bottom and sides and having extending ends to swing down and form a two-section cover 40 for the box, said sections having flexible end edges adapted to overlap along the central part of the box top, said blank composed of longitudinal bottom, side and cover wall-

forming sheets traversed and connected by exterior wire-bound battens stapled thereto. 45

6. A packing box comprising end heads, and a continuous web blank secured around the same to form a two-part cover, sides and bottom of the box, said blank consisting of sheets arranged longitudinally of the box 50 and exterior wire-bound battens secured to and connecting and arranged transversely of said sheets and continued across the joints between the bottom, sides and cover, and transversely cut to bend at said joints, said 55 battens terminating short of either end of the blank to form a flexible projecting end edge adapted to overlap the opposite free end of the blank about at the longitudinal central line of the two-part cover. 60

7. A packing box comprising end heads, and a web blank adapted to bend around and be secured thereto to form the longitudinal walls of the box and comprising spaced sheets and wire-bound exterior battens traversing said sheets and secured thereto and bridging the spaces between the sheets, said battens having transverse cuts to form the bending lines at the corners of the box, said bending lines being arranged 65 transversely of the portions of the battens bridging said spaces, the bending line at each corner being arranged near one sheet edge and removed from the adjacent sheet edge whereby the edge of one sheet abuts against 70 the batten between the bending line and the edge of the adjacent sheet with the edge of the adjacent sheet bearing against the inner face of said first mentioned sheet, substantially as and for the purposes described. 75

In testimony whereof I affix my signature, in presence of two witnesses.

JOHN SHELLENBERGER.
